TOWEL RACK

Earl A. Wheeler, Bakersfield, Calif.; Gertrude Lee
Wheeler administratrix of said Earl A. Wheeler,
deceased

Application June 8, 1948, Serial No. 146,821

Term of patent 14 years

(Cl. D33—16)

To all whom it may concern:

Be it known that I, Earl A. Wheeler, a citizen of the United States, residing in the city of Bakersfield, county of Kern, State of California, have invented a new, original, and ornamental Design for a Towel Rack, of which the following is a specification, reference being had to the accompanying drawing, forming a part thereof.

Fig. 1 is a plan view of a towel rack, showing my new design.

Fig. 2 is a front elevation of the towel rack as illustrated in Fig. 1.

Fig. 3 is an end elevation of the towel rack, viewing Fig. 2 from its left end.

I claim:

The ornamental design for a towel rack, as shown.

EARL A. WHEELER.
